[57] **CLAIM**

The ornamental design for an automobile spoiler, substantially as shown and described.

DESCRIPTION

FIG. 1 is a perspective view of an automobile spoiler showing my new design;

FIG. 2 is a front elevation view thereof;

FIG. 3 is a top plan view thereof;

FIG. 4 is an end elevation view thereof;

FIG. 5 is a perspective view of an automobile spoiler showing a second embodiment of my new design;

FIG. 6 is a front elevation view of FIG. 5;

FIG. 7 is a top plan view of FIG. 5;

FIG. 8 is an end elevation view of FIG. 5;

FIG. 9 is a perspective view of an automobile spoiler showing a third embodiment of my new design;

FIG. 10 is a front elevation view of FIG. 9;

FIG. 11 is a top plan view of FIG. 9;

FIG. 12 is an end elevation view of FIG. 9;

FIG. 13 is a perspective view of an automobile spoiler showing a fourth embodiment of my new design;

FIG. 14 is a front elevation view of FIG. 13;

FIG. 15 is a top plan view of FIG. 13; and

FIG. 16 is an end elevation view of FIG. 13.
